(57) **CLAIM**

The ornamental design for a furniture component, as shown and described.

DESCRIPTION

The file of this patent contains two photographs executed in color. Copies of this patent with the color photographs will be provided by the Office upon request and payment of the necessary fee.

FIG. 1 is a front elevational view of a furniture component showing my new design.

FIG. 2 is an enlarged front elevational view thereof; and, FIG. 3 is a vertical cross-sectional view taken along line 3—3 of FIG. 2, depicting surface configuration thereof.

A horizontal cross-sectional view thereof along line 3—3 of FIG. 2 is identical to FIG. 3.

The rear thereof forms no part of the claimed design.

The broken lines shown in FIG. 1 depict the environment of the design and form no part of my claimed design.
